UNITED STATES PATENT OFFICE.

EDWARD T. REDDING, OF SWISSVALE, PENNSYLVANIA, ASSIGNOR TO CONSOLIDATED EXPANDED METAL COMPANIES, A CORPORATION OF PENNSYLVANIA.

EXPANDED-METAL-MAKING APPARATUS.

Application filed July 30, 1921. Serial No. 488,569.

To all whom it may concern:

Be it known that I, EDWARD T. REDDING, a citizen of the United States, residing at Swissvale, in the county of Allegheny and 5 State of Pennsylvania, have invented certain new and useful Improvements in Expanded-Metal-Making Apparatus, of which the following is a specification.

This invention relates to apparatus for 10 making expanded metal fabric. In certain of such apparatus, particularly that used in following the so-called Golding process in which the diamonds are formed by a shearing operation, there is a tendency to curl or 15 distort the end diamonds of a sheet, this curling being especially noticeable in fabric of large mesh, such, for example, as a road fabric.

One of the primary objects of my invention 20 is to overcome this difficulty and to thereby improve the product, reduce the cost and the wastage, and to facilitate packing.

The foregoing, together with such other objects as may hereinafter appear, or are incident to my invention, I obtain by means of 25 a construction illustrated in preferred form in the accompanying drawings, wherein:

Fig. 1 is a front elevation of one form of 30 shearing machine equipped with my improvements; Fig. 2 is a fragmentary cross section illustrating such improvements in side elevation and on an enlarged scale; Fig. 3 is a section on the line 3—3 of Fig. 2; Fig. 4 is a fragmentary section and side elevation, showing the parts in another position; Fig. 5 is a plan view of Fig. 4 with the 35 machine parts omitted; Fig. 6 is a front elevation of Fig. 4; Fig. 7 is a view corresponding to Fig. 6, but illustrating the parts in a different position; and Fig. 8 is a view illustrating the distortion of the 40 end of a sheet which it is sought to avoid.

Referring now to Figs. 1 and 2, it will be 45 sufficient to point out, as to the machine in general, that it includes the vertically reciprocating member A having a plurality of half-diamond shearing dies 10; the table member B having a die 11; and the horizontally reciprocable frame C, comprising 50 the bars 12 and 13 operated by the cam mechanism D, the blank 14 to be expanded being supported on the upper part of the frame C so as to be shifted therewith but being capable of being advanced as the expanding is in progress. The construction 55

and operation of these parts is well understood in the art, and it will suffice to point out that when the blank has been shifted (relative to the dies 10) to the position to shear the half-diamonds *a* no difficulty is 60 encountered; but when the blank is in the position shown in Fig. 3, (relative to the dies 10) to shear loose the other half of the diamonds, the end bridges *a'* are unsupported so that the dies, in shearing, tend to 65 turn down the bridge and crumple up the strands *b*, as illustrated in Fig. 8, producing a ragged, uneven end on the sheet.

I overcome the objectionable feature described by supporting the end bridge portion *a'* of each diamond during the shearing loose of the second half thereof. This is done by the following means: I mount yielding supports, indicated as a whole by 70 the letter E, on the bar 13 of the frame C 75 so as to move therewith, such supports being located so as to come adjacent the ends of the sheet being formed in position to support the end bridges as they are sheared.

The supports are composed of a main 80 vertical plate 15 to the front edge of which is secured a member 16 having a groove providing an undercut shoulder 17 at the top cooperating with a removable wedge member 18 to fit the bar 13 and adjustably 85 lock the support in any desired position longitudinally of the bar; the grooved member 19 which slidably receives a bar 20, the upper end 21 of which is turned in to engage under the bridge; and the spring 90 held lever 22 which yieldingly holds the bar 20 against the lower face of the bridge. The tension of the spring 23 is adjusted by 95 the wing nut 24, and the stroke of the lever by the set screw 25.

When the parts are in the position of Fig. 7, the end 21 of the bar engages the edge of the blank but performs little, if any, function during the shearing operation there indicated. When the parts have shifted to the 100 position of Fig. 3 for forming the other half of the diamonds, during which operation the bridge *a'* will be sheared loose, it will be seen that the bar 20 yieldingly supports the bridge 105 and prevents the crumpling of the end strands and the turning down of the bridge. In Figs. 2 and 3 the dies 10 are in upper position just before the beginning of the down stroke and in Figs. 4 and 6, they have completed their down shearing stroke, and from 110

inspection of these figures it will be understood how the bridge is held laterally against the end dies to prevent the distortion, while at the same time the bar 20 yields to permit of the descent of the dies.

The operation is simple and effective, the parts are always in operative position and the supports may be adjusted to suit sheets of different widths.

10 I claim:

1. The combination with a guillotine machine for making expanded metal fabric of the Golding type, of means for holding an end portion of the sheet laterally against the moving shearing die permitting movement of the die to shear such portion loose.

2. The combination with a guillotine machine for making expanded metal fabric of the Golding type, of means moving with the shearing die for laterally supporting an end portion of the sheet while such portion is being sheared loose by the die.

3. The combination with a guillotine machine for making expanded metal fabric of

the Golding type, of means for laterally engaging and yieldingly supporting an end portion of the sheet against the shearing die while such portion is being sheared loose by the die.

4. The combination with a guillotine machine for making expanded metal fabric of the Golding type, of means for laterally supporting an end portion of the sheet while such portion is being sheared loose by the shearing die, said means comprising a member spring pressed against such portion opposite the die.

5. A guillotine machine for making expanded metal fabric of the Golding type comprising a horizontally reciprocable frame for shifting the sheet to be operated on, and means moving with said frame for laterally supporting an end portion of the sheet while being sheared loose.

In testimony whereof, I have hereunto signed my name.

EDWARD T. REDDING.
